UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed July 6, 1922. Serial No. 573,141.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

The present invention relates to means, in combination with the rotary platen of a typewriting machine, for facilitating and rendering more accurate and expeditious the operations involved in the stenciling or printing of cards, such, for instance, as stencil address cards. More particularly, the invention relates to means, of the character mentioned, for use in a front-strike machine, and which provide for introduction of the cards downward, bottom end first, at the front of the platen, to printing or stenciling position, and for a line-spacing and ejecting movement of the cards with the platen in the usual direction.

A stencil card usually consists of a small piece of stencil paper having a frame or border which consists of cardboard, and this frame is usually of such material that it is not desired to bend the stencil card around the platen. Another difficulty that has been experienced in handling these cards is that they are not easily controlled by the platen and the feeding devices co-operating therewith, so that the cards are liable to skew at the line-feeding operations. It has been proposed to place the card in a frame and to gear the frame to the platen, so as to effect positive line-feeding of the card, but this requires expensive and bulky mechanism for which there is usually no room in a front-strike typewriting machine.

For preventing skewing of the cards in the feed of the same, while avoiding the use of all such special frames, it has been proposed to equip the platen with bands of fine teeth, for indenting the margins of the cards, and to provide spring-fingers for holding the margins of the cards to the toothed bands with pressure sufficient to effect such indenting, when, by rotation of

the platen, the margins of the cards are introduced between the spring-fingers and the toothed bands.

An object of the invention is the provision of toothed bands on the platen, for the purposes mentioned; which bands, however, are of a design enabling the same to operate on cards of different widths, or on cards in different adjusted positions on the platen. In this connection, a feature of the invention is the provision of means whereby the fingers, which co-operate with the bands, may be adjusted lengthwise of the platen, with respect to the bands, according to the width or desired position of the card to be used.

A further object of the invention is the provision of a platen having a plurality of stenciling or printing fields thereon, one in advance of the other, and preferably represented by separate, replaceable strips or pieces of celluloid or other suitable material; either of which fields may be selected and used for the stenciling of addresses, or inscriptions of a few lines, on the cards; and one of which fields may be substituted for another, by turning the platen to a new setting, when the celluloid or backing on a field becomes worn. In the use of such a platen, the delays and inconvenience incident to replacements or readjustments of the celluloid or other backs are reduced to a minimum.

Other features of the invention are means on the platen for aligning or gaging the cards thereon preliminary to indentation thereof by the toothed bands; fixed means on the platen, engageable by the celluloid strips, to hold the latter in place, while permitting ready detachment of the same for replacement; and means whereby the strip-holding means may serve as the card-gages.

A further object of the invention is the provision of means for effecting and determining, as to any selected one of the stenciling fields, a movement of the card with the platen, downward bottom end first, at the front of the platen, to stenciling or printing position, and line-spacing and card-ejecting movements of the card with

the platen in opposite direction; and for releasing the means which determine the movements of the platen for a given stenciling field, so that the platen may be set for 5 another of the fields, and the controls again set for that field.

Another feature of the invention is the provision of a stop-device to which the platen may be connected to have movement 10 therewith between normally fixed stops, but with respect to which the platen may also have a differential movement; thus providing for ample throw of the platen, while permitting the fixed stops and the carrier 15 therefor to be set, and to be movable between effective and ineffective positions, in a small space, unobstructed by other parts.

A feature of the invention is a construction 20 of the fingers for holding the cards to the toothed bands; which construction, as to each finger, may combine with the finger-proper, in a single, cheaply made, sheet-metal piece, a chute, various aligning means 25 for the cards, and a stop for determining the position for printing on the top margins of the cards; and which, as a unitary and separately manufactured article, may be quickly and easily attached to or replaced in the machine.

30 Other features and advantages will hereinafter appear.

In the accompanying drawings,

Figure 1 is a top plan view of the carriage 35 of a typewriting machine equipped with the devices of the present invention.

Figure 2 is a front view of the apparatus shown in Figure 1.

Figure 3 is a view in side elevation, partly 40 in cross-section, taken on the line 3—3 of Figure 1; the parts, with a stencil-card in place, being shown in position preliminary to reverse movement of the platen to bring the card down to the printing position.

45 Figure 4 is a view similar to Figure 3, except that the parts are shown as having been moved to position to print upon the top margin of the card; the stop-device being also shown in dotted line or in ineffective position.

50 Figure 5 is a view, in cross-section, through the platen on the line 5—5 of Figure 1.

55 Figure 6 is a front view of the platen indicating the use of cards of different dimensions in connection with the toothed bands.

Figure 7 is a view in perspective of the right-hand end of the platen.

60 Figure 8 is a perspective view of the stop-disk for the right-hand end of the platen, being shown as spread away from the Figure 7 view of the platen, more clearly to show the details in their proper relations.

Fig. 9 is a top plan view of the front of

one of the bands; the pressure-finger being 65 shown in cross-section in its relation to the band.

Figure 10 is a view similar to Figure 9, except that the card is shown as having been 70 inserted between the band and the finger.

The invention is shown as applied to an Underwood typewriting machine. The drawings show the platen-frame found in such a machine. This frame comprises side plates 10, having laterally-offset portions or 75 flanges 11 on their upper edges. A bar 12 connects and holds the plates 10 together at the rear, and, at the front and below the platen, the plates are connected by a rod 13. The rod 13 normally serves as a support for 80 the levers which carry the front and rear pressure-rolls (not shown). A rod 14, revolvably supported below the rod 13, serves to throw the pressure-rolls. The plates 10 are also connected by a rod 15, which commonly 85 serves as a paper-finger-rod.

For making card-stencils, a short platen is ordinarily employed. The short platen 16, in the present instance, however, is carried, and in part formed, by a longer 90 metal cylinder 17, having heads 18 secured in the ends thereof, by screws 19, and having end plates 20 in which is centered the shaft 21, on which the cylinder is revolvably mounted in the end plates 10 of the casing. 95 The shaft 21 passes through the plates 10, and, on its ends, carries the usual hand wheels or knobs 22, by which the platen may be rotated. Also, on the shaft 21, at the left of the platen-frame, is the usual 100 ratchet or line-space wheel 23, in which runs a detent-roll 24, mounted on a spring-pressed arm 25, forming part of the line-spacing mechanism. The latter mechanism 105 also includes a handle 26, which returns the carriage-frame and carriage to the beginning of a new line; this handle usually having an arm 27, to press back a slide 28, and thereby operate a pawl 29, which engages the ratchet-wheel 23.

110 The platen proper is shown as centrally located on the metal cylinder 17. It comprises a rubber-sleeve 30, closely fitted onto the cylinder 17, at each end of the rubber-sleeve 115 30, is a metal ring or band 32. The rings or bands 32 have their surfaces toothed, as shown at 33, to grip the side borders 34 of the stencil-card. The bands 32 are preferably of such width as to grip cards of different widths, or to permit lateral adjustment of the cards on the platen, while presenting an effective gripping surface. To accommodate themselves to cards of different widths, the rings 32 are flat, and the teeth thereof extend laterally across the same, from edge to edge. Effectively to grip the cards, only a slight indentation of the

margins 34 thereof, by the teeth 33, when the cards are pressed against the bands by means presently to be described, is necessary. Consequently, the teeth may be quite fine, and need project but very slightly beyond the stenciling surface of the platen. The teeth 33 are shown as continued entirely around the bands 32, although, as will hereinafter appear, the teeth at certain parts of the periphery of the bands are not utilized, and might, therefore, be omitted.

The stenciling is effected against one or another of a plurality of strips 35, of celluloid, held to the face of the rubber-sleeve 30, by plates 36. The plates 36 extend longitudinally of the platen, from one to the other of the bands or rings 32, and are secured to the platen by screws 37, which pass through the plates and through the rubber-sleeve 30, and thread into the metal cylinder 17. Two of these plates are shown, on opposite sides of the platen. The forward and rear edges of the plates are undercut, as shown at 38, to receive and hold the edges 25 of the celluloid pieces 35. Each plate 36 holds the front edge of one celluloid piece and the rear edge of the other celluloid piece. The walls or ledges which determine the undercuts 38 serve as gages for positioning and aligning the celluloid facings. The strips of celluloid may be slightly bent to be sprung into the undercuts in the plates 36, and, when worn, may be pulled out. More easily to permit the removal of a piece 35 of celluloid, the plates 36 are shown as each having a recess 39, in one edge thereof, to allow insertion of a finger beyond the edge of the celluloid.

For guiding the stencil-cards onto the platen, and for holding the same with a gripping pressure against the toothed rings or bands 32, sheet-metal fingers 40 are provided. These fingers have ears 41, to receive screws 42, for supporting the fingers 40 on offsets or flanges 43 on the forward ends of arms 44. There are two arms 44, one for supporting each of the fingers, and these arms, at their rear ends, connect to a rod 45, which extends from one to another of the platen-frame end pieces 10, and is flattened at its ends, to receive screws 46, by means of which it is secured to the platen-frame. The arms 44 are recessed intermediate their length, to receive the rod 15, which assists in supporting the arms, and which prevents rotary movement of the same on the shaft 45. Set-screws or thumb-screws 47 fix the position of the arms 44, to set the fingers 40 in proper position with respect to the toothed wheels. Preferably the arms 44, together with the fingers 40, are adjustable, lengthwise of the platen, for cards of different widths.

At their upper ends, the fingers are inclined, at 48, from a position above the

platen, downward and forward toward the front surface of the platen, to guide the cards down into position. The inclined portions 48 of the fingers are also provided with forwardly-offset flanges 49, to serve as 70 gages for the side margins of the stencil-cards. The incline 48 on each finger terminates in a lateral cut 50 in the finger; the finger being bent out at 51, below the cut 50, across the path of the card being 75 pushed down the incline. The lower margin of the card, as the latter is fed down into position, strikes the offsets 51, and is thereby guided to a ledge 52 formed upon the upper edge of the forward plate 36. 80 This ledge 52 serves as a gage properly to align the lower edge of the card. Below the offsets 51, the fingers 40 are extended, as at 53, down around the platen, opposite the toothed rings 32, and finally terminate 85 in ledges 54, adjacent the rod 14. The spring-set of the fingers 40 is such as to cause the same to press toward the toothed rings with sufficient force to cause the side margins of the stencil-cards, forced between 90 the fingers and the rings by rotation of the platen, to be indented by the teeth, and so gripped as to prevent slipping and skewing as the card is brought to printing position. Engagement of the lower edge of 95 the card with the ledges 54, at the lower ends of the fingers, may determine the position for writing on the top margin of the card, as shown in Figure 4. As shown at 100 51^a, in Figure 1, the card-gripping portions of the fingers are inclined laterally toward the toothed bands. The slit 51^b, which allows for the offset 51, also weakens the connection of the finger-proper to its supporting ear 41; so that the finger-proper may yield laterally with respect to the ear, as 105 well as, as a whole, forward. Slits 49^a permit the forward ends of the ears or side gages 49 on the chute 48 to be turned out laterally as at 49^b; so that, if the top margin of the card is fed beyond the ears 49 in the movement to printing position, the card will again enter the chute without obstruction on movement of the platen in line-space or ejecting direction.

Ordinarily, for stenciling cards of the character contemplated, only quite a limited rotation of the platen is required. Thus it becomes feasible to provide for a plurality of stenciling surfaces on the platen, as is exemplified by the use of the two strips of celluloid to serve as backs against which the stenciling is done. One of these celluloid surfaces may be used until worn, and then, without immediately replacing the same, the platen may be turned to bring the other celluloid surface into use. Provision is, therefore, made for two different rotary movements of the platen, to wit, a movement between certain limits for the po- 115 120 125 130

sitioning and stenciling of the card in one of the celluloid fields, and another movement to set the platen for use of the other celluloid field when the first is worn or is to be discontinued. These movements of the platen are effected and determined as follows.

Journalized on the platen-shaft, at the right-hand side, to have limited rotary movement of the shaft, with respect to the platen, is a disk 55. The movement of the disk 55, relative to the platen, is provided for, and determined, by arcuate slots 56 in the disk, through which slots pass shou-
19 dered screws 57, threading into the head of the platen. In feeding the card from its initial, Figure 3, position (after its lower margin has been brought to rest on the ledge 52), to printing position, the platen
20 may have a limited movement, independent of the disk 55, until the screw 57 reaches the end of the slot 56, whereupon the platen will pick up the disk and carry the same until the disk is arrested by means presently
25 to be described; or, if friction causes the disk to participate in the initial movement of the platen, then, after the disk is arrested, the movement of the platen may be continued until the screw 57 has traversed the
30 length of the slot 56. In this manner, in bringing the card to printing position, provision is made for a greater movement of the platen than of the disk; and the stops which control the movement of the disk may
35 be set closer together than might otherwise be practicable.

The stops, which control the movement of the disk 55, in each celluloid stenciling field, consist of a pin 58, fast to, and projecting outward to the right from, the disk, and two normally stationary fingers 59 and 60, between which the pin 58 has play. In Figure 3, when the card is set on the ledge 52, preparatory to movement of the same with the platen to printing position, the pin 58 is shown as in contact with the finger 59. When the disk is picked up by the screw 57, upon rotation of the platen, the pin 58 is carried in the direction of the arrow to the finger 60, by means of which finger it is arrested, and, when so arrested, the disk, in turn, arrests and determines the movement of the platen to card-stenciling position. On contact of the screw 57 with the right-hand end of the slot 56, as the line-space mechanism is actuated in the stenciling operation, the platen has movement in the opposite direction, first relatively to the disk (unless friction causes the disk to move with the platen), and then with the disk until the pin 58 on the disk is arrested by the finger 59, and the screw 57 on the platen is arrested by engagement with the left-hand end of the slot 56; the parts being thus moved back from Figure 4 position to Fig-

ure 3 position. It will be understood that the operation thus described involves stenciling on one only of the celluloid fields.

When stenciling on the other celluloid field is desired, the stops 59 and 60 are lifted from the path of the pin 58, to permit the platen to be given a half revolution with the disk 55, to bring the other pin 58^a on the disk into the field previously occupied by the pin 58. To permit the fingers 59 and 60 thus to be lifted, the same are formed on a plate 61, pivoted at 62, on a shouldered screw, threaded into a bracket 63. The bracket 63 sits astride the left-hand frame-member 10, and is secured thereto by a screw 64. When the plate 61 is swung around its pivot 62, the fingers 59 and 60 are lifted out of the path of the pins 58 and 58^a; and, for effecting this movement of the plate 61, the same is provided with a finger-piece 65. A spring 66, secured at one end to the plate 61, and at its other end to the bracket 63, normally holds the plate 61 with the fingers 59 and 60 in effective, Figure 3, position, and returns the same to such position when the finger-piece 65 is released. The plate 61 has an arcuate groove therein, to permit the same to straddle, and be moved with respect to, the rod 15, connecting the frame-members 10.

When the plate 61 is lifted to dotted line, Figure 4, position, the platen is free to be turned by the hand-wheels, or by the line-spacing mechanism, until the pin 58^a is in the field previously occupied by the pin 58, and one celluloid piece occupies the position previously occupied by the other. Thereupon the plate 61 is released to the action of the spring 66, to set the stops 59 and 60 for the pin 58^a. Thereafter the movements of the platen and of the disk 55 are as heretofore noted, except that these movements are controlled by the pin 58^a, instead of by the pin 58. Two pin-and-slot connections 56-57 are shown between the disk 55 and the platen, but these act as one, and one might be omitted except that the two serve to hold the disk in vertical position. The movement of the platen relative to the disk 55 may also be omitted where a small movement of the platen will suffice, or whenever it is practicable to spread the stops 59 and 60 so far apart as in themselves to determine the desired movement of the platen. The pin-and-slot connection of the disk to the platen, however, permits the stop mechanism to be condensed in a small space, and to be set well clear of such standard structural features as might otherwise interfere with the same.

Certain features herein disclosed are made the subject-matter of the application of Burnham C. Stickney, Serial No. 532,188, filed January 27, 1922, upon which the present invention is an improvement.

Variations may be resorted to within the scope of the invention, and portions of the improvements may be used without others.

Having thus described my invention, I claim:

1. The combination with a rotary platen having sharp teeth, set around the periphery thereof, for indenting, and thus gripping, work-pieces by their margins, of a spring-
10 finger for holding the margins of the work-pieces against the teeth with pressure sufficient to cause the teeth to indent the margins; said finger depending across the printing line at the front of the platen and being
15 inclined downward and rearward above the printing line to form with the toothed band a throat for guiding the margins of the work-pieces into contact with the teeth, and means for guiding the work-pieces forward
20 and downward into contact with said downward and rearward incline.

2. The combination with a rotary platen having sharp teeth, set around the periphery thereof, for indenting, and thus gripping, work-pieces by their margins, of a spring-
25 finger for holding the margins of the work-pieces against the teeth with pressure sufficient to cause the teeth to indent the margins; said finger depending across the printing line at the front of the platen and being
30 inclined downward and rearward above the printing line to form with the toothed band a throat for guiding the margins of the work-pieces into contact with the teeth, a
35 chute forming a part of the spring for guiding the work-pieces forward and downward into contact with said downward and rearward incline, and an ear offset forward from the chute portion of the spring to serve as a
40 gage for the side margin of the work-piece.

3. The combination with a rotary platen having sharp teeth, set around the periphery thereof, for indenting, and thus gripping, work-pieces by their margins, of a spring-
45 finger for holding the margins of the work-pieces against the teeth with pressure sufficient to cause the teeth to indent the margins; said finger depending across the printing line at the front of the platen and being
50 inclined downward and rearward above the printing line to form with the toothed band a throat for guiding the margins of the work-pieces into contact with the teeth, and a chute for guiding the work-pieces forward
55 and downward into contact with said downward and rearward incline; the chute and the throat portions of the spring being in alignment, and the spring being slit between these parts thereof to permit passage of the
60 work-piece from the front of the chute to the rear of the throat part.

4. The combination with a rotary platen having sharp teeth, set around the periphery thereof, for indenting, and thus gripping, work-pieces by their margins, of a spring-

finger for holding the margins of the work-pieces against the teeth with pressure sufficient to cause the teeth to indent the margins; said finger depending across the printing line at the front of the platen and being
70 inclined downward and rearward above the printing line to form with the toothed band a throat for guiding the margins of the work-pieces into contact with the teeth, means for guiding the work-pieces forward
75 and downward into contact with said downward and rearward incline, and a gage on the platen for movement with the platen to the apex of the throat, to receive and position the lower margin of the work-piece preliminary to movement of the platen with the work-piece to printing position.

5. The combination with a rotary platen having sharp teeth, set around the periphery thereof, for indenting, and thus gripping, work-pieces by their margins, of a spring-
85 finger for holding the margins of the work-pieces against the teeth with pressure sufficient to cause the teeth to indent the margins; said finger depending across the printing line at the front of the platen and being
90 inclined downward and rearward above the printing line to form with the toothed band a throat for guiding the margins of the work-pieces into contact with the teeth, and a gage on the platen for movement with the platen to the apex of the throat, to receive and position the lower margin of the work-piece preliminary to movement of the platen with the work-piece to printing position.

6. The combination with a rotary platen having sharp teeth, set around the periphery thereof, for indenting, and thus gripping, work-pieces by their margins, of a spring-
100 finger for holding the margins of the work-pieces against the teeth with pressure sufficient to cause the teeth to indent the margins; said finger depending across the printing line at the front of the platen and being
105 inclined downward and rearward above the printing line to form with the toothed band a throat for guiding the margins of the work-pieces into contact with the teeth, and a gage formed on the spring below the printing line to determine the downward throw
110 of the work-piece.

7. The combination with a rotary platen having sharp teeth, set around the periphery thereof, for indenting, and thus gripping, work-pieces by their margins, of a spring-
120 finger for holding the margins of the work-pieces against the teeth with pressure sufficient to cause the teeth to indent the margins; said finger depending across the printing line at the front of the platen and being
125 inclined downward and rearward above the printing line to form with the toothed band a throat for guiding the margins of the work-pieces into contact with the teeth, and being also inclined laterally to bite the
130

side margin of the work-piece along a certain line thereof.

8. The combination with a rotary platen having sharp teeth, set around the periphery thereof, for indenting, and thus gripping, work-pieces by their margins, of a spring-finger for holding the margins of the work-pieces against the teeth with pressure sufficient to cause the teeth to indent the margins; said finger being rigidly supported above the printing line, outside of the field of the toothed band, and being laterally offset to overlie such field; the finger being slit part-way along the line of its lateral offset, 15 for flexibility of such offset.

9. The combination with a rotary platen having sharp teeth, set around the periphery thereof, for indenting, and thus gripping, work-pieces by their margins, of a spring-finger for holding the margins of the work-pieces against the teeth with pressure sufficient to cause the teeth to indent the margins; said finger being rigidly supported above the printing line, outside of 20 the field of the toothed band, and being laterally offset to overlie such field; the finger being slit part-way along the line of its lateral offset, for flexibility of such offset, and being offset forward and upward, along the 25 line of the slit, to form, with the toothed band, a throat for guiding the work-pieces to gripping position.

10. The combination with a rotary platen having sharp teeth, set around the periphery thereof, for indenting, and thus gripping, work-pieces by their margins, of a spring-finger for holding the margins of the work-pieces against the teeth with pressure sufficient to cause the teeth to indent the margins; said finger depending across 35 the printing line at the front of the platen and being inclined downward and rearward above the printing line to form with the toothed band a throat for guiding the 40 margins of the work-pieces into contact with the teeth, a chute forming a part of the spring for guiding the work-pieces forward and downward into contact with said 45 downward and rearward incline, and an ear offset forward from the chute portion of 50 the spring to serve as a gage for the side margin of the work-piece; the lower end of the ear being turned out laterally to assure that the top margin of a work-piece, 55 which may have been fed beyond the same in moving with the platen to printing position, may pass back into the chute on movement of the platen in the opposite direction.

11. The combination with a platen, of 60 means for determining a limited rotary movement thereof, comprising a plate having an axis around which it is movable, a stop for arresting such movement of the plate, and a loose connection between the 65 plate and the platen; whereby the plate and

platen may be turned together until the plate is arrested by its stop, and the platen thereafter turned further in the same direction an extent determined by the looseness of the connection of the same to the 70 plate.

12. The combination with a platen, of means for determining a limited rotary movement thereof, comprising a plate having an axis around which it is movable, 75 stops, one for arresting such movement of the plate, in each direction, and a loose connection between the plate and the platen; whereby the plate and platen may be turned together, in either direction, until the plate is arrested by one of its stops, and the platen thereafter turned further in the same direction an extent determined by the looseness of the connection of the same to the 80 plate.

13. The combination with a platen, of means for determining a rotary movement thereof, comprising a plate having an axis around which it is movable, a stop for arresting such movement of the plate, a loose connection between the plate and the platen; 85 whereby the plate and platen may be turned together until the plate is arrested by its stop, and the platen thereafter turned further in the same direction an extent determined by the looseness of the connection of the same to the plate, and means for rendering the plate-stop ineffective, at will. 90

14. The combination with a platen, of means for determining a limited rotary movement thereof, comprising a plate revolvable on the axis of the platen, a tooth on the plate, a pair of stops, one to each side of the tooth, for arresting rotation of the plate after a predetermined movement thereof in either direction, a pin-and-slot connection between the plate and the platen; whereby the plate and the platen may be turned together, in either direction, until the tooth on the plate strikes one of the stops, and the platen thereafter turned further in the same direction an extent determined by the length of the slot, a carrier for the plate-stops, and means for moving the carrier with the plate-stops to ineffective position, out of the path of the pin on the plate. 110

15. The combination with a platen having two stenciling fields thereon, one in advance of the other, of means for determining the rotary movement of the platen, for stenciling in either field, and for bringing either field thereof into use, comprising a plate having an axis around which it is movable, a tooth on the plate, a pair of stops, one to each side of the tooth, for arresting rotation of the plate after a predetermined movement thereof in either direction, a loose connection between the plate and the platen, whereby the plate and platen may be turned together, in either direction, in one stenciling field, and the platen thereafter turned further in 120 125 130

the same direction in such field an extent determined by the looseness of the connection of the platen to the plate, a carrier for the plate-stops, means for moving the carrier 5 with the stops to ineffective position to permit the platen to be turned to bring the other stenciling field into use, and another tooth on the plate adapted to co-operate with the stops on the carrier when the latter is 10 again moved to effective position after interchange of stenciling fields.

16. The combination with a platen having two stencilling fields thereon, one in advance of the other, of means for determining the 15 rotary movement of the platen, for stencilling in either field, and for bringing either field thereof into use, comprising a pair of detents connected to the platen, one for each stencilling field, a pair of stops, one on each 20 side of the detent for the field in use for arresting the movement of the platen in either direction in such field, a carrier for the stops, and means for moving the carrier with the stops to ineffective position, to permit 25 the platen to be turned to bring the detent for the other field into position for co-operation with the stops on the carrier.

17. In a typewriting machine, a rotary platen, a plurality of strips of celluloid, or 30 other material suitable as a stencilling ground, on the surface of the platen, and plates secured to the platen to hold the strips in place, and serving as gages for aligning the margins of the stencil cards when engaged 35 thereby.

18. In a typewriting machine, a rotary platen, a plurality of strips of celluloid, or other material suitable as a stencilling ground, on the surface of the platen, one in 40 advance of the other, and plates secured to the platen between such strips and overlapping the edges of the strips to hold the latter to the platen.

19. In a typewriting machine, a rotary platen, a plurality of strips of celluloid, or other material suitable as a stencilling ground, on the surface of the platen, one in advance of the other, and plates secured to the platen between such strips and at opposite 55 edges to overlap the edges of the strips to hold the latter to the platen.

20. In a typewriting machine, a rotary platen, a strip of celluloid, or other material suitable as a stencilling ground, on 55 the surface of the platen, and a plate secured to the platen, extending longitudinally thereof and overlapping the edge of the strip to hold the latter to the platen; the edge of the plate being recessed to permit 60 engagement of the edge of the strip by the operator's finger for removal of the strip.

21. In a typewriting machine, a rotary platen, a plurality of strips of celluloid, or other material suitable as a stencilling 65 ground, on the surface of the platen, one

in advance of the other, plates secured to the platen between such strips and overlapping the edges of the strips to hold the latter to the platen, sharp teeth, set in bands around the periphery of the platen at the 70 ends of the strips and plates, for indenting and thus gripping the stencil cards by the side margins thereof, and spring fingers for holding the margins of the cards against the toothed bands with pressure sufficient to 75 cause the teeth to indent the margins.

22. In a typewriting machine, a platen frame, a platen cylinder journaled in and extending substantially from one to the other of the side pieces of the platen frame, 80 and a short platen telescoped by the cylinder at an intermediate part of the latter.

23. In a typewriting machine, a platen frame, a platen cylinder journaled in and extending substantially from one to the 85 other of the side pieces of the platen frame, a short platen telescoped by the cylinder at an intermediate part of the latter, and bands of teeth secured to the cylinder at the edges of the platen for gripping the side margins 90 of stencil cards.

24. In a typewriting machine, the combination with a revoluble platen having intermediate its ends two rings of teeth for indenting and thus gripping work-pieces by 95 their margins, of means to press the work-pieces against such toothed rings, to cause such indenting, and a gage in the form of a ledge on said platen and extending longitudinally thereof, for engaging an edge of 100 a work-piece to assure proper positioning thereof preparatory to feeding the same into typing position and indenting the margins thereof.

25. In a typewriting machine, the combination with a revoluble platen having intermediate its ends two rings of teeth for indenting and thus gripping work-pieces by 105 their margins, of means to press the work-pieces against such toothed rings, to cause such indenting, and a longitudinal gage on said platen to assure alignment of said work-pieces preparatory to indentation while permitting adjustment thereof longitudinally 110 of the platen.

26. In a typewriter, the combination of a rotary platen provided at two portions on opposite sides of the middle with a wide zone or band composed of sharp teeth, which zones are spaced to engage the end portions of the usual stencil-member and which zones are each of a width to permit engagement of different widths of stencil-members within a relatively wide range of sizes, and a pair of spring fingers each arranged to press the end portion of the stencil against the toothed bands to emboss the work and cause interengagement, thereby to prevent slip of the stencil on turning the platen. 120

27. In a typewriter, the combination of 130

at rotary platen provided at two portions on opposite sides of the middle with a wide zone or band composed of sharp teeth, which zones are spaced to engage the end portions 5 of the usual stencil-member and which zones are of a width to permit engagement of different widths of stencil-members within the relatively wide range of sizes, and a pair of spring fingers each arranged to press

the end portions of work-pieces against the 10 toothed bands to emboss the work and cause interengagement, thereby preventing slip of the stencils on turning the platen, said fingers being shiftable along said bands for engagement with the margins of different widths of stencil-members. 15
